United States Patent Office.

ALBERT J. STEELE, OF NEW YORK, N. Y.

Letters Patent No. 73,207, dated January 7, 1868.

UTERINE ELECTRODE AND ABDOMINAL SUPPORTER.

The Schedule referred to in these Letters Patent and making part of the same.

TO ALL WHOM IT MAY CONCERN:

Be it known that I, A. J. STEELE, of the city, county, and State of New York, have invented a new and improved Uterine Electrode and Abdominal Supporter; and I do hereby declare that the following is a full, clear, and exact description thereof, which will enable others skilled in the art to make and use the same, reference being had to the accompanying drawings forming part of this specification, in which—

Figure 1 is a perspective view of the electrode attached to the supporter.

Figure 2 is a detail view of the manner of securing the electrode in place.

Figures 3, 4, and 5 are forms of electrodes.

Similar letters of reference indicate corresponding parts.

This invention relates to the application of electricity to the uterus and vagina when these organs are in different pathological conditions.

It consists of insulated wires bent in suitable shapes, and covered with sponge or other equivalent substance, for providing a medium of conduction from the insulated wire to the diseased part.

The different forms of the electrode are shown, each having special advantages in different conditions of the uterus or vagina, but the principle of my invention is common to all, which is the construction of a wire or conductor of electricity, bent into certain forms, and insulated with hard rubber, gutta percha, or other suitable material. These forms are then covered with sponge, or other soft absorbent substance, and one or more small holes are made in the insulating-sheath, at that part of the electrode which is in juxtaposition with the part of the vagina or uterus that is diseased. The electrode is connected with one pole of a battery or electro-magnetic machine, and a current of electricity passed through the wire form, the patient grasping the other pole of the battery.

An abdominal belt, A, of any suitable fabric, is made in two parts, the said parts being united by lacing-strings, as shown at *a a*. Flaps *b b* prevent the cords from irritating the skin beneath. Attached to the belt is a strap, B, the posterior attachment of this strap being elastic straps *c c*, and the anterior attachment being a buckle, E, as shown in figs. 1 and 2. This strap is attached at the lower middle edges of the two parts of the belt A, and passes between the legs when in place. A plate, D, of horn, hard rubber, or other suitable non-conducting material, is secured to the inner surface of the strap B, and this plate is provided with a number of slots, *d d*, for inserting the looped end of the electrode, as shown at fig. 2. A small clasp-hook, *e*, then is hooked into the said looped end, and connected with the battery or machine. The electrode shown at fig. 3 is designed for applying the electricity to the anterior and posterior sides of the uterus, and is provided with a bifurcating stem, *ff*, a ring, *g*, cross-pieces, *h*, and a loop, *j*, for attaching the electrode to the plate D. That shown at fig. 4, for applying the electricity to the neck of the uterus, has stems *f' f'* and ring *g'*. In these electrodes the supporting-stems, the rings for contact with the diseased organ, the cross-pieces for similar object, and the loop *j*, are of any conducting-wire, bent and soldered in these forms. In figs. 3 and 4, a removed section, *k*, shows the wire and its insulating-sheath. Fig. 5 is a simpler form of electrode, constructed on the same principle as the others.

When applied, the sponge-covering of the electrode is moistened with water, thus rendering the same a conductor, and the electrode connected with battery. If the organ requires treatment at its anterior or posterior sides, or both, the electrode at fig. 3 is to be used, the insulating-sheath having been tapped or punctured accordingly by the practitioner, at the cross-pieces *h h*. If the neck of the uterus or the vagina requires treatment, the rings *g* or *g'*, or stems *f f'*, are tapped in one or more places, as shown by the dots *n n n n' n' n'*.

The belt A can be used as an abdominal supporter, with or without the electrode attachments. The straps *c* provide a yielding tension to the strap B, whereby the wearer can sit down without being in the slightest degree incommoded by the presence of the electrode when in place. The skeleton of these electrodes being of wire, can be easily bent by the patient or practitioner in such forms as may be found best when adjusting the same.

In addition to the advantages already mentioned, this method of applying electricity to the diseased organ is so simple that the electrodes can be used by the patient after a few precepts, thus avoiding the indelicacy of personal application by the practitioner.

Having thus described my invention, what I claim as new, and desire to secure by Letters Patent, is—

1. Wire electrodes, insulated and covered with sponge, substantially as shown, and for the purpose specified.
2. The strap B, for sustaining the electrode in place, substantially as shown and for the purpose specified.
3. The form of electrode having a ring, g' , and stems ff' attached thereto, substantially as shown and for the purpose specified.
4. The form of electrode having the ring g and cross-pieces $h\ h$, substantially as shown and for the purpose specified.
5. The form of electrode having a single stem, f'' , and cross-piece h' , substantially as and for the purpose shown and described.
6. Elastic straps $c\ c$, in combination with the strap B, substantially as and for the purpose shown and described.
7. The abdominal belt A, in combination with the above-described electrodes, substantially as and for the purposes shown and described.
8. The non-conducting plate D, in combination with the wire electrodes, as hereinafter described, substantially as shown and for the purpose specified.

ALBERT J. STEELE.
